UNITED STATES PATENT OFFICE.

CHARLES EGAN, OF ZANESVILLE, OHIO, ASSIGNOR TO GEORGE M. JEWETT,
OF SAME PLACE.

MECHANICAL TELEPHONE.

SPECIFICATION forming part of Letters Patent No. 269,030, dated December 12, 1882.

Application filed May 16, 1882. (No model.)

To all whom it may concern:

Be it known that I, CHARLES EGAN, of Zanesville, in the county of Muskingum and State of Ohio, have invented a new and useful Improvement in Mechanical Telephones, of which the following is a full, clear, and exact description.

The object of my invention is to increase upon the line the vibrations given to the diaphragm by the voice, so as to insure greater loudness and clearness of tone; and to that end the invention consists in employing two diaphragms, which are connected by wires that diverge from the center of the outer diaphragm, and are attached to the inner one at points between its center and edge, as shown and described.

Reference is to be had to the accompanying drawings, forming a part of this specification, in which similar letters of reference indicate corresponding parts in all the figures.

Figure 1 is a front view of the instrument. Fig. 2 is a cross-section of the same. Fig. 3 is a face view of the multiplying-diaphragm.

25 A is the base upon which the instrument is supported by posts *a a*.

B is the instrument proper, of which *b* is the apertured bottom piece, and *c* is a box fitted with mouth-piece *d*.

30 *e* is a diaphragm fitted beneath the mouth-piece *d*; and *f* is a second diaphragm, fitted over the aperture in the bottom piece, *b*.

g g are wires, preferably four in number, connected at the center of the diaphragm *e*, and also connected at their other ends to the diaphragm *f* about half-way between its center and outer end. Wires *g* are taut, and to the center of the second diaphragm, *f*, is connected the main wire *h*.

In operation the outer diaphragm, *e*, being 40 vibrated by the act of speaking into the mouth-piece, the vibrations are communicated by the wires *g* to the second diaphragm, *f*, and the wires *g* being connected at a distance from the center of the diaphragm *f*, the vibrations are 45 consequently amplified at the center of the second diaphragm, and these amplified vibrations pass upon the main-line wire.

The instrument is provided with an electric call-bell, *i*, and circuit-closer *k* for calling in 50 the usual manner.

Having thus described my invention, I claim as new and desire to secure by Letters Patent—

The combination of two diaphragms and the wires *g*, which are attached to the outer diaphragm at its center, diverging thence toward the inner one, to which they are connected at points between its center and edge, substantially as described.

CHARLES EGAN.
